(57) **CLAIM**

The ornamental design for an orbital implant for human ocular support, as shown and described.

DESCRIPTION

FIG. 1 is a superior view of a orbital implant for human ocular support shown in our new design (the inferior view is the same);

FIG. 2 is a right side view thereof (the left side view is the same);

FIG. 3 is an anterior view thereof;

FIG. 4 is a lateral isometric view thereof;

FIG. 5 is a superior view of a second embodiment of a orbital implant for human ocular support shown in our new design (the inferior view is the same);

FIG. 6 is a right side view of the second embodiment thereof (the left side view is the same);

FIG. 7 is an anterior view of the second embodiment thereof; FIG. 8 is a lateral isometric view of the second embodiment thereof;

FIG. 9 is a superior view of a third embodiment of a orbital implant for human ocular support shown in our new design (the inferior view is the same);

FIG. 10 is a right side view of the third embodiment thereof (the left side view is the same);

FIG. 11 is an anterior view of the third embodiment thereof; FIG. 12 is a lateral isometric view of the third embodiment thereof;

FIG. 13 is a superior view of a fourth embodiment of a orbital implant for human ocular support shown in our new design (the inferior view is the same);

FIG. 14 is a right side view of the fourth embodiment thereof (the left side view is the same);

FIG. 15 is an anterior view of the fourth embodiment thereof; and,

FIG. 16 is a lateral isometric view of the fourth embodiment thereof.
